(57) **CLAIM**

The ornamental design for a lighter holder with a storage container assembly as shown and described.

DESCRIPTION

FIG. 1 is a perspective view of the lighter holder with a storage container assembly;

FIG. 2 is a front view of the lighter holder with a storage container assembly of FIG. 1;

FIG. 3 is a rear view of the lighter holder with a storage container assembly of FIG. 1;

FIG. 4 is a side view of the lighter holder with a storage container assembly of FIG. 1;

FIG. 5 is a side view of lighter holder with a storage container assembly of FIG. 1;

FIG. 6 is a top view of the lighter holder with a storage container assembly of FIG. 1;

FIG. 7 is a bottom view of the lighter holder with a storage container assembly of FIG. 1; and,

FIG. 8 is an exploded perspective view of the lighter holder with a storage container assembly in an open configuration. The lighter holder with a storage container assembly is shown with a symbolic break in its length. The appearance of any portion of the article between the break lines forms no part of the claimed design.
